UNITED STATES PATENT OFFICE.

OTTO HAENTJENS, OF HAZLETON, PENNSYLVANIA.

PUMP SYSTEM.

Application filed January 28, 1926. Serial No. 84,409.

My invention relates to pump systems, and particularly to a pump system of the general type indicated in my Patent No. 1,513,705, in which a centrifugal pump is primed by the action of an associated suction pump connected to the casing of the centrifugal. In systems of this type the priming operation is effected by exhausting air from the casing of the centrifugal by the action of the auxiliary suction pump, so that water rises through the intake line into the casing of the centrifugal. The object of my invention is to provide means for temporarily sealing the casing packings of the centrifugal runner shaft, so that air leakage into the centrifugal casing is prevented during the priming operation.

When a centrifugal pump has been operated for a considerable length of time, the usual runner shaft packings at the casing walls, wear to such an extent that there is considerable air leakage at these points into the runner casing while the latter is being evacuated by the priming pump. This air leakage may be so great as to seriously retard, or even prevent, the priming operation. To avoid this difficulty, a seal which is temporarily effective during the priming operation, suffices. Moreover, inasmuch as the seal is needed only to prevent inward leakage of air, it need not be of such character that it prevents outward leakage of water when the pump is in operation.

The temporary seal may be of any appropriate character, such as a water seal (Figs. 1 to 3) or a sealing washer (Figs. 4 to 6), both of which are illustrated in the accompanying drawings, in which

Fig. 1 is a side elevation showing a centrifugal pump with associated temporary water seal for the stuffing boxes;

Fig. 2 is a section through one of the centrifugal pump stuffing boxes, drawn to a larger scale;

Fig. 3 is a diagrammatic sketch of the electrical connections by which the water seal means may be controlled to automatically establish the seal only while the priming pump is in operation;

Fig. 4 is a section similar to Fig. 2, but showing a temporarily operative sealing washer;

Fig. 5 is a plan view thereof; and

Fig. 6 is a section on the line 6—6, Fig. 5. The centrifugal pump comprises a casing 10, through the opposite sides of which

passes the pump runner shaft 11, supported in bearings 12—13 exterior to the casing. At the opposite sides of the centrifugal casing the runner shaft passes through stuffing boxes 14—15, within which are the usual packing rings 16. Glands 17—18 bear against the packing rings 16 to maintain the latter tight. In the course of time, however, the rings 16 wear and do not prevent inward leakage of air through the stuffing boxes to the interior of the pump casing when the latter is evacuated for priming. The priming operation is therefore greatly retarded or fails.

To remedy this difficulty in the manner indicated in Figs. 1—3, I provide each gland with a water chamber 19 surrounding the shaft 11 and having a lateral inlet 20, through which water may enter the chamber 19 and form a seal at the stuffing box. Seal water is supplied to the glands from the pipe 21, branches 22 and 23 of which respectively deliver to funnels 24 and 25, which open to the inlets 20 of the glands.

Any suitable means may control the water supply through the pipe 21, so that water is delivered to the glands only during the priming operation. For example, when the pipe 21 is connected to a water main, a self-closing, solenoid-opened valve may be used. I have shown, however, a self-contained system in which the pipe 22 is connected to a seal water pump 26. The latter, which may be a small rotary pump, is supplied with water from a tank 27, to which drain pipes 28 and 29 return the over-flow from the glands 17 and 18. The seal water thus follows a closed circuit, which includes the glands. When the centrifugal is in operation, outward water leakage, from the pump chamber through the stuffing boxes, is caught in the drains and adds to the supply in the tank 27, thus keeping the latter full to the level of its over-flow outlet 30.

Inasmuch as the seal water is supplied to the stuffing boxes only during the priming operation, the operating solenoid 31 of switch 32 which controls the circuit of an electrical motor 33 for driving the seal water pump 26, may be arranged in a priming pump control circuit 34 of the general type shown in my Patent No. 1,513,705. In this system the priming pump control circuit 34 is automatically closed and opened by a switch 35 operated by a float in the sump. Consequently when the sump switch

35 closes, not only is the priming pump started, but also the seal water pump, so that during the priming operation the water seal is established. Obviously upon the 10 automatic opening of the priming pump control circuit at 36, when the centrifugal is under way, (as explained in my patent above mentioned) the seal water pump is also halted. If a self-closing solenoid-operated valve is substituted for the seal water pump, as above suggested, the breaking of the solenoid circuit permits the valve to automatically close, thus shutting off the seal water supply in analogous fashion.

15 A less expensive arrangement is shown in Figs. 4-6 inclusive, in which a sealing washer is substituted for the water seal. Here the gland 37 is of usual type and is pressed against the packing rings 16 by springs 38 beneath the nuts 39 on the ends of the bolts 40. The sealing washer 41 which prevents air leakage through the stuffing box during the priming operation, is pressed against the end of the gland 37 by the sliding collar 42, 25 Since the seal is needed only during priming, and since constant pressure of the washer against the gland would cause its rapid wear, I provide pressure means which are effective only when the pump is not running.

For this purpose the collar 42 is engaged by one end of each of the leaf springs 43-44, which are anchored at their opposite ends to a sleeve 45, and provided intermediate their ends with weights 46. The sleeve 45 may be directly attached to the shaft 11 of the centrifugal, or adjustably connected as shown. The adjustable connection may be effected through a nut 47 threaded onto the exterior of the sleeve and bearing, under the thrust of the springs 43-44 against the abutment ring 48 fastened by set screws 49 to the shaft 11. Obviously the stress of the springs 43-44 may be varied by screwing the nut 47 on sleeve 45. But the nut 47 and abutment 48 may be omitted; in which case the set screws 49 will pass through the sleeve 45 and secure it directly in predetermined position on the shaft 11.

During the priming operation, before the centrifugal is under way, and therefore while the shaft 11 is stationary, the springs 43-44, and collar 42, force the sealing washer 41 against the gland 37 and prevent air leakage around the shaft through the stuffing box. When the pump is primed and under way, however, the rotation of the shaft is imparted to the springs 43-44, and centrifugal force exerted thereon (and increased by the weights 46) causes the retraction of collar 42, thus relieving the sealing washer 41 from wear.

Other ways of accomplishing the same result in accordance with the thoughts which

underlie my invention, will doubtless occur to those dealing with the problem without departing from what I claim as my invention.

I claim—

1. In a priming system, a centrifugal pump casing, a shaft passing through the casing, a stationary packing for the shaft at the point at which it passes through the casing, means for evacuating the casing, and means temporarily effective to seal the packing against air leakage into the casing during the evacuation of the latter. 70

2. In a priming system, a centrifugal pump casing, a shaft passing through the casing, a stationary packing for the shaft at the point at which it passes through the casing, means for evacuating the casing, and means for temporarily forming a water seal at the packing during the evacuation of the casing. 80

3. In a priming system, a centrifugal pump casing, a shaft passing through the casing, a packing for the shaft at the point at which it passes through the casing, means for evacuating the centrifugal casing, means for establishing a seal at the packing, and an electric control circuit common to said evacuating means and seal-establishing means. 90

4. In a priming system, a centrifugal pump casing, a shaft passing through the casing, a packing for the shaft at the point at which it passes through the casing, means for evacuating the centrifugal casing, means for establishing a flow of seal water to the packing, and an electric control circuit common to said evacuating means and seal water flow means. 100

5. In a priming system, a centrifugal pump casing, a shaft passing through the casing, a packing for the shaft at the point at which it passes through the casing, an electrically operated pump for evacuating the casing of the centrifugal, an electrically operated water flow device for delivering seal water to said packing, and a control circuit common to said pump and water flow device for simultaneously operating the same. 105

6. In a priming system, a centrifugal pump casing, a shaft passing through the casing, a packing for the shaft at the point at which it passes through the casing, an electrically operated pump for evacuating the casing of the centrifugal, an electrically operated pump for delivering seal water to said packing, and means for simultaneously operating said evacuating and seal water pumps. 120

7. In combination, a pump casing, a runner shaft passing therethrough, a packing for the runner shaft, and means for circulating water in a circuit including said packing to form a water seal at the packing. 125

8. In a priming system, a centrifugal pump casing, a shaft passing through the pump casing, a shaft passing through the casing, a stationary packing for the shaft, a packing for the shaft at the point at which it passes through the casing, means for evacuating the centrifugal pump casing, and means inoperative when the centrifugal pump is under way for sealing the casing against air leakage around the shaft. 15
- 5 for evacuating the casing, means for sealing the packing against air leakage into the casing during the evacuation of the latter, and means automatically operative to render the said sealing means ineffective when the pump is under way. In testimony whereof I have signed my name to this specification.
- 10 9. In a priming system, a centrifugal
